UNITED STATES PATENT OFFICE.

JOHN ARCHIBALD BEATON, OF WHARTON, NEW JERSEY.

GAS-BURNER.

1,332,791.

Specification of Letters Patent.

Patented Mar. 2, 1920.

Application filed June 14, 1918. Serial No. 240,051.

To all whom it may concern:

Be it known that I, JOHN A. BEATON, a citizen of the United States, residing at Wharton, in the county of Morris and State 5 of New Jersey, have invented new and useful Improvements in Gas-Burners, of which the following is a specification.

This invention relates to new and useful 10 improvements in gas burners and the principal object of the invention is to so arrange the parts that an even pressure of the gas is secured in its passage through the gas intake.

Other objects of the invention reside in the 15 peculiar arrangement of the air nozzle within the gas intake, the means for moving said nozzle and intake as an integral part, and the means for controlling the passage of air through the nozzle.

Another object of the invention is to provide 20 a device of this character which is simple and durable in construction, reliable and efficient in operation and one which can be manufactured and placed upon the market at a minimum cost.

The invention also consists in certain other 25 features of construction and in the combination and arrangement of the several parts, to be hereinafter fully described, illustrated 30 in the accompanying drawings and specifically pointed out in the appended claims.

In describing my invention in detail, reference will be had to the accompanying drawings wherein like characters denote like 35 or corresponding parts throughout the several views, and in which:—

Figure 1 is an elevation of the invention.

Fig. 2 is a plan view.

Fig. 3 is a longitudinal section.

Fig. 4 is a perspective view of the air control shutter and its operating lever.

In these views the gas intake, indicated 45 by the reference numeral 10 is provided with a base 11 which is slidably mounted on a gas chest 12. Said chest is connected with a suitable source of gas supply. As shown, the intake 10 is of elongated form with curved walls. The rear end of said intake is enlarged with the walls converging to

50 the throat 13. Adjacent this throat the intake is provided with an outwardly extending flange 14 to which the flange 15 of the outlet nozzle 16 is bolted. As will be seen the throat opens into the constricted end 55 of said nozzle. 17 indicates the air nozzle located within the gas intake. This nozzle

is provided with an enlarged rear end of curved formation and the upper and lower walls converge forwardly to a point a slight distance in rear of the throat 13. The rear 60 and lower walls of the nozzle come together and extend downwardly to form a wedge-shaped partition 18 which divides the gas inlet in the base 11 into two parts 19 and 20. The air nozzle divides the gas intake into 65 two gas conduits 21 and 22 which are connected with the parts 19 and 20. The conduit 21 extends around the rear end of the nozzle and above the upper wall thereof to the throat 13 while the conduit 22 is located 70 under the lower wall of the air nozzle. A large port 23 is formed in each side of the air nozzle and practically embraces the whole side so that these sides of the nozzle are open to the atmosphere. The passage of 75 air through the nozzle is controlled by a balanced shutter 24, which is located adjacent the forward end of the air nozzle. This shutter is provided with the trunnions 25 and 26. The trunnion 26 is provided with a 80 square end 27. Webs 28 are formed in the forward end of the nozzle adjacent the edges thereof and these webs are provided with the sockets 29 in which the trunnions 25 and 26 of the shutter engage. As will be seen 85 the trunnion 26 is of greater length than that 25 and passes through the wall of the gas intake with its square end 27 projecting from said wall. This square end engages a square opening 30 formed in the end of an operating handle 31. This handle is provided with a bar 32 suitably secured thereto and having its free end spaced therefrom. 33 is a sector shaped member suitably secured 90 to the intake and engaged by the handle and bar. These parts are so formed as to frictionally engage said member so that the shutter may be adjusted in any desired position in the air nozzle. Openings 34 are formed in the ends of the intake and communicate with the gas conduits 21 and 22. These openings are closed by the doors 35 suitably secured in position and adapted to be removed when access is to be had to said conduits.

The rear part of the device is provided 100 with wings 36 having bearings 37 at their ends, in which is journaled a shaft 38. This shaft is provided with a hand wheel 39 and a pinion 40, which is located between the 105 journals. This pinion engages with a stationary rack 41 carried by the chest 12 so

that by operating the hand wheel the entire device, consisting of the intake, the air nozzle and the outlet nozzle 16 may be moved toward and from the furnace A. It will be seen that as the device is withdrawn from the furnace the gas inlets leading from the chest will be closed, thus shutting off the supply of gas.

An important part of my invention resides in the location of the air nozzle in relation to the gas intake. Attention is called to the fact that said nozzle is located in rear of the constricted part or throat of said intake. In this way said nozzle will not affect the pressure of the gas by acting as a baffle, as it will be seen that the pressure of the gas in both conduits will be the same.

It is thought from the foregoing description that the advantages and novel features of my invention will be readily apparent.

I desire it to be understood that I may make changes in the construction and in the combination and arrangement of the several parts, provided that such changes fall within the scope of the appended claims.

Having thus described my invention, what is claimed is:—

1. A gas burner comprising a gas intake having a constricted part forming a throat, an air nozzle located within said intake and dividing said intake into two conduits each consisting of a horizontal portion and a vertical portion, means for connecting the vertical portions with a gas supply and means for connecting the sides of the nozzle with the atmosphere.

2. A gas burner comprising a gas intake having a constricted part forming a throat, an air nozzle located within said intake to the rear of said throat and dividing said intake into an upper and lower gas conduit, each conduit consisting of a horizontal portion and a vertical portion, means for connecting the vertical portions with a gas supply, means for connecting the edges of the air nozzle with the atmosphere, a shutter in said nozzle adjacent the outlet end thereof and means for controlling the position of said shutter.

3. A gas burner comprising a gas intake, an air nozzle located in said intake and dividing the same into two conduits, each conduit comprising a horizontal part and a vertical part, said air nozzle having a wedge-shaped projection at its lower part extending downwardly and separating the vertical parts of the conduit, means for connecting said vertical parts with a gas supply and means for connecting the sides of the air nozzle with the atmosphere.

4. A gas burner comprising a gas chest, a gas intake having its base slidably mounted on said chest, a rack and gearings for sliding said intake, an air nozzle in said intake dividing the same into a pair of conduits, each conduit consisting of a horizontal part and a vertical part, the vertical parts being in communication with the gas chest and doors for affording access to the horizontal parts.

In testimony whereof I affix my signature.
JOHN ARCHIBALD BEATON.
